UNITED STATES PATENT OFFICE.

HARVEY M. GERSMAN, OF CHICAGO, ILLINOIS.

EXPANDED METAL.

Application filed June 1, 1923. Serial No. 642,872.

This invention relates to improvements in expanded metal and involves features which are applicable generically to various forms of structural members and, in connection with other features, are specifically applicable to metal sheets, i. e., lathing, it being understood that the invention is claimed in both aspects.

"Herringbone" is the name applied to a formed of expanded metal lathing which is characterized by parallel webs and by spaced parallel strands extending between and connecting the adjacent webs. In so far as expanded metal of the present invention conforms to these broadly stated characteristics of herringbone metal it may be conveniently designated as of the herringbone type; but as compared with herringbone metal as heretofore known the metal of the present invention possesses radical and important features of difference in which the invention consists.

The distinguishing features involve, broadly stated, the mutual relation of the webs and the strands and the structure of the parts or portions by which the webs and strands are connected. As regards the mutual relation of the webs and the strands the expansion is developed whereby the strands lie flat in a common plane and the bends or breaks in the strands are located at the same, i. e., corresponding, sides of adjacent webs. Where the metal is produced in the form of sheets, i. e., lathing, the webs are flat and co-planar and their common plane is preferably offset from and parallel to the common plane of the strands, it being understood that sheets having this preferred characteristic may be either single-sided, i. e., with all the strands in a common plane or double-sided, i. e., with the strands of alternate rows in parallel planes. As regards the structure of the portions by which the webs and strands are connected the metal is characterized by definite offsets in planes normal to the planes of the strands, and the breaks, so-called, i. e., lines of bending transverse to the strands, occur in the offsets. In addition there is a second break in the strand itself extending diagonally between its edges and providing a re-enforcing rib or shoulder which is effective in a direction at an angle to the direction of the webs while the offsets provide re-enforcing ribs which are effective in the directions of the webs.

A general advantage of substantial importance is a marked increase of stiffness and also intrinsic strength in both directions, i. e., width and length, without increase of weight. Lathing embodying the features of the invention has the following substantial advantages as compared with herringbone metal as heretofore known: The sheets by reason of their increased stiffness are easier to handle when fitting to supporting members and hanging or wiring in place; the full value of the surfaces of the webs is utilized in opposing resistance to plaster, thus avoiding cutting through and loss by seepage; greater resistance is opposed to the pressure of the trowel, thus avoiding the use of an excess amount of plaster for lining up; the supporting members may be placed on wider centers, the advantage of ribbed lathing being thereby secured; due to the definite spacing of the expanded portions by the webs good keying effects can be obtained with the use of substantially less plaster; and a greater proportion of solid metal to voids is obtained. The single sided sheet having the preferred characteristic above mentioned has the additional advantage of being completely self furring.

The invention is illustrated in the accompanying drawings in the form of sheet lath together with blanks from which the metal may be produced. It will, however, be understood that the form of the blank and the method of expansion may be varied and that in any case the invention herein claimed is not to be regarded as limited to details of any particular blank or method of expansion.

In said drawings:

Figure 1 is an elevation of the outer or obverse face of a fragmentary portion of either a single or double-sided sheet.

Figure 2 is a cross sectional view on the line 2—2 of Figure 1.

Figure 3 is a longitudinal sectional view on the line 3—3 of Figure 2.

Figure 4 is an elevation showing an initial stage in the formation of the blank for a single-sided sheet.

Figure 5 shows the blank ready for expansion.

Figure 6 is a section on the line 6—6 of Figure 5.

Figure 7 is a cross section of the blank shown in Figure 5.

Figure 8 is an elevation of the outer or obverse face of a fragmentary portion of the sheet expanded from the blank of Figure 5, and is drawn to a scale conforming to the scale of Figures 4 to 7.

Figure 9 shows the blank for a double-sided sheet.

Figure 10 is a section on the line 10—10 of Figure 9.

10 Figure 11 is a cross section of the blank shown in Figure 9.

Figure 12 is a perspective view of the form of my invention shown in Figure 1.

Referring to Figures 1, 2, 3 and 12:

15 These figures illustrate a fragment of an expanded metal sheet having parallel imperforate portions or webs 12 and expanded portions between the imperforate portions, the expanded portions being characterized 20 by spaced parallel strands 13 which preferably extend diagonally between the adjacent webs. The strands 13 of each expanded portion lie flat in a common plane and, according to the invention, the connections 25 by which they are joined to the adjacent webs 12 are disposed at the same, that is to say corresponding, sides of said webs which, as parts of lathing, also lie flat in a common plane. The connections between the strands 30 and the webs include portions 14 which are offset from the webs in planes normal to the common plane of the strands. The common plane of the strands is preferably offset from and parallel to the common plane of 35 the webs, the offsets 14 determining the elevation of the strands relatively to the webs. The offsets 14 are arranged at the sides of the webs and along each side provide, in functional effect, a rib parallel to the web and 40 which reinforces the sheet in the longitudinal direction, considering the webs as extending lengthwise of the sheet. The strands have at their ends angular portions 15 which extend from the offsets 14 and 45 may be regarded as angular extensions of the offsets, the portions 15 being delimited by breaks, i. e., lines of bending, 16 and 17 which extend at angles to one another from the corners of the offsets remote from the 50 webs. The breaks 16 lie in the plane of the offsets and extend to the web, forming the common bases of polygons which are delimited by the offsets and their angular extensions 15, such polygons being triangular 55 in the preferred construction disclosed. The breaks 17 lie in the planes of the strands and provide a series of ribs which reinforce the expanded portions of the sheet in generally transverse directions, that is to say directions 60 at an angle to the lengthwise direction of the webs.

Figures 1, 2, 3 and 12 show two adjacent webs 12 and an expanded portion between them and it will be understood that the

fragment shown may be regarded as either 65 of a single sided sheet or a double sided sheet. In a single sided sheet all of the expanded portions are arranged at the same, i. e., corresponding, sides of the webs, such a sheet being completely self furring. In 70 a double sided sheet the expanded portions are arranged alternately at opposite sides of the webs. The strands preferably extend diagonally and may extend all in the same direction or, as preferred, in the alternate expanded portions they may extend 75 in opposite directions.

Metal conforming to the invention may be produced in different ways and from blanks having different characteristics but in all 80 cases the blanks must be preformed whereby the breaks at both ends of the strand will occur at the same sides of the adjacent webs in relation to offsets lying in planes substantially normal to the webs. The specific structure disclosed may, as embodied 85 in single sided sheets, be produced from the blank shown in Figures 5, 6 and 7 and as embodied in double sided sheets be produced from the blank shown in Figures 9, 90 10 and 11. It will be understood however that the illustration of the blanks and the description to follow of the method of expansion is not to be taken as imposing any 95 limitation to a particular form of blank or 100 to a particular method, the present invention consisting wholly in the structure.

Referring to Figures 4, 5, 6 and 7:

The blank is produced from a section of flat metal formed with rows of slits 18 100 (Figure 4), the slits of each row delimiting the area in which expansion is effected and the imperforate spaces 19 between the rows of slits being available for the webs. As shown the slits are arranged diagonally, extending in opposite directions in the alternate rows. The flat section provided with the slits, as described, is then longitudinally 105 corrugated to provide the completed blank shown in Figures 5, 6 and 7. The longitudinal corrugations are alternately inverse and consist of corrugations 20 presenting channels to the obverse face of the blank and corrugations 21 presenting channels to the reverse face of the blank. The adjoining 110 inverse corrugations have common sides which are struck up along the opposite sides of the slotted portions whereby the slits 18 extend throughout the bases and sides of the corrugations 21. The completed blank is 115 then expanded or stretched in a direction of its mean plane. With the specific form of blank disclosed the alternate portions 19 are rotated in the same direction in their common plane with reference to the remaining portions 19 which are held against 120 rotation. In case all of the slits of the blank should extend in the same direction 125

(as where it is desired to have all of the strands extend in the same direction) the blank is held at one side only and all of the remaining portions 19 are rotated in the same direction but in relative succession, a step-by-step rotative effect being thus obtained. The stretching of the blank in the above manner will result in expanded metal having the characteristics described, 10 a larger fragment drawn to the scale of Figures 4 to 7 being shown in Figure 8. In connection with the expansion of the blank disclosed the portions of metal which provide the sides of the corrugations 15 21 are utilized for the offsets 14 and extensions 15. This will be apparent by reference to Figure 6 from which it will be observed that the sides of the corrugations are made of uniform conterminous portions, 20 each of rhomboidal outline, whereof the pairs of adjacent sides which form the acute angles are the sides of the triangles delimited by the offsets 14 and the extensions 15, the sides which adjoin the bases of the 25 corrugations 21 coincide with the breaks 17, and lines taken as common intersectors of the obtuse angles coincide with the breaks 16 developed during the expansion.

Referring to Figures 9, 10 and 11: 30 In this case the blank is formed with longitudinal corrugations 21^a and 21^b corresponding functionally to the longitudinal corrugations 21 of the preceding example but formed alternately inversely and at the 35 opposite sides of the co-planar imperforate portions 19 by which the sides of the adjacent inverse corrugations are connected, the slits 18, as before, being extended through the sides of the corrugations to 40 the imperforate portions. The method of expansion is precisely the same as in the preceding example but the form of the blank results in double sided expanded sheets, that is to say sheets wherein the 45 strands 13 of alternate expanded portions lie at opposite sides of the webs 12.

Having fully described my invention, I claim:

1. Expanded metal characterized by imperforate parallel webs and expanded portions between the adjacent webs, each expanded portion consisting of spaced parallel strands lying flat in a common plane and connected at their ends to the adjacent webs 50 by portions offset from said webs along their edges in planes normal to the common plane of the strands, the offsets projecting from corresponding sides of the webs.

2. Expanded metal characterized by imperforate parallel webs and expanded portions between the adjacent webs, each expanded portion consisting of spaced parallel strands lying flat in a common plane and connected at their ends to the adjacent webs 60 by portions projecting from the edges of said

webs and in which the lines of bending incident to the provision of the strands occur at corresponding sides of the webs.

3. Expanded metal characterized by imperforate parallel webs and expanded portions between the adjacent webs, each expanded portion consisting of spaced parallel strands lying flat in a common plane and connected at their ends to the adjacent webs by portions offset from said webs along 70 their edges in planes normal to the common plane of the strands, the offsets projecting from corresponding sides of the webs and the plane of the strands being offset relatively to the webs.

4. Expanded metal lath characterized by imperforate parallel webs lying flat in a common plane and expanded portions between the adjacent webs, each expanded portion consisting of spaced parallel strands 80 lying flat in a common plane and connected at their ends to the adjacent webs by portions offset from said webs along their edges in planes normal to said common planes of the webs and the strands, the offsets projecting from corresponding sides of the webs.

5. Expanded metal lath characterized by imperforate parallel webs lying flat in a common plane and expanded portions between the adjacent webs, each expanded portion consisting of spaced parallel strands lying flat in a common plane and connected at their ends to the adjacent webs by portions projecting from the edges of said webs 90 and in which the lines of bending incident to the provision of the strands occur at corresponding sides of the webs.

6. Expanded metal lath characterized by imperforate parallel webs lying flat in a common plane and expanded portions between the adjacent webs, each expanded portion consisting of spaced parallel strands lying flat in a common plane and connected at their ends to the adjacent webs by portions offset from said webs in planes normal to said common planes of the webs and the strands, the offsets projecting from corresponding sides of the webs and the plane of the strands being offset from and parallel 105 to the plane of the webs, the elevation of the plane of the strands being determined by the offsets by which the strands are connected to the webs.

7. Expanded metal characterized by imperforate parallel webs and expanded portions between the adjacent webs, each expanded portion consisting of spaced parallel strands lying flat in a common plane and connected at their ends to the adjacent webs by portions offset from said webs along 120 their edges in planes normal to the common plane of the strands, the offsets projecting from corresponding sides of the webs and having angular extensions by which they 125

are joined to the strands whereby a line of bending occurs in the plane of each offset and a second line of bending at an angle to the first occurs in the plane of the adjacent strand.

8. Expanded metal characterized by imperforate parallel webs and expanded portions between the adjacent webs, each expanded portion consisting of spaced parallel strands lying flat in a common plane and connected at their ends to the adjacent webs by portions offset from said webs

along their edges in planes normal to the common plane of the strands, the offsets projecting from corresponding sides of the webs and having angular extensions by which they are joined to the strands whereby a line of bending occurs in the plane of each offset and a second line of bending at an angle to the first occurs in the plane of the adjacent strands, the plane of the strands being offset relatively to the webs.

In testimony whereof I affix my signature.
HARVEY M. GERSMAN.
